(57) **CLAIM**

The ornamental design for a decorative cylinder, as shown and described.

DESCRIPTION

FIG. 1 is an environmental perspective view of a decorative cylinder showing my new design;

FIG. 2 is a front elevational view, with the right and the left elevational views being identical, thereof;

FIG. 3 is a rear elevational view thereof;

FIG. 4 is a top view thereof; and,

FIG. 5 is a bottom view thereof.

The broken line showing of the skyline in FIG. 1 is for illustrative purposes, merely showing the types of decoration which can be put on the invention, and forms no part of the claimed design.

The fragmented crosshatch pattern shown in the drawing represents fabric and is repeated throughout the areas shown.
